L. M. BOATMAN

REBORING TOOL

Filed Sept. 14, 1923.

Lloyd M. Boatman, Inventor.

BY
O. O. Overholts

ATTORNEY.

UNITED STATES PATENT OFFICE.

LLOYD M. BOATMAN, OF NEMAHIA, NEBRASKA.

REBORING TOOL.

Application filed September 14, 1923. Serial No. 662,742.

To all whom it may concern:

Be it known that I, LLOYD M. BOATMAN, a citizen of the United States, residing at Nemaha, in the county of Nemaha and State of Nebraska, have invented certain new and useful Improvements in Reborning Tools, of which the following is a specification.

My invention relates to a reboring tool for engine cylinders.

10 My object is to provide a device of this character having a suitable cutter provided with a guide which fits the cylinder both in advance of the cutter and also after it, so that the rebored hole forming the inside 15 wall of the cylinder will be exceptionally true.

Another object is to provide a device of this character which will readily clear itself 20 of the shavings or cuttings bored from the cylinder, so that the cutting edge of the 25 knife can always be kept clean and free from the accumulation of borings around it.

Another object is to provide a device of this character which while very simple in 30 its construction, will yet provide such a strong and positive guide for the cutter, and will hold it so true to its work, that only one cutter will be required, thus avoiding the necessity of having a plurality of 35 cutters arranged in pairs on diametrically opposite sides of the centre of the device in order to get a true bore.

Other objects will appear in the subjoined description.

35 An important feature of my device consists of a guiding cylinder having its forward end portion in advance of the cutter of a size to fit the opening to be rebored, and the portion following the cutter of a 40 size to fit the rebored part of the opening.

The invention consists in the novel construction and arrangement of the several parts, as will be hereinafter described and claimed, reference being had to the accompanying drawings, in which:—

Fig. 1 is a vertical section through one of my devices.

Fig. 2 is a side elevation on a reduced scale of the device arranged for boring by hand; and, Fig. 3 is a view, on a still further reduced scale, illustrating means for holding the device to its work when reboring by hand.

Referring further to the drawings, the 55 numeral 1 indicates a guide cylinder having an interior wrist pin 2 for revolving the

cylinder. This wrist pin may be either rigidly connected to the cylinder or may be formed integral therewith. Rigidly or integrally connected to the wrist pin midway between its ends is a key post 3 adapted to be engaged by a universal joint 4 carried on a power shaft 5. The lower portion 4^a of the universal joint is removably connected with the key post 3, in any suitable manner.

Suitably mounted on top of the wrist pin 2 is a tool post 6 of ordinary or preferred construction, having a set screw 7 for securing the tool 8 in operative position.

The lower portion 1^a of the guide cylinder, which extends up to the under side of the cutter 8, is of a diameter equal to that of the hole to be rebored, while the upper portion 1^b is of a diameter equal to that of the cylinder after it is rebored; so that my guide cylinder fits the hole that is being rebored, both in advance of the cutter 8 and also following it.

The portions 1^a and 1^b of the cylinder are connected together by an inclined annular shoulder 1^c.

The guide cylinder is provided in its wall with an opening 9 through which the cutter 8 projects to engage the work. The rear side of the cutter rests against the rear wall of the opening, with the opening practically in front of the cutter, so to speak, which permits the particles of displaced metal to fall through said opening to the inside of the guide cylinder; and as this cylinder is made with both ends open, the borings easily fall out through either end thereof, thus keeping the edge of the cutter clean and free from any accumulation of borings. It will also be seen that this arrangement keeps the tool from springing from its work or from chattering, so that an unusually true bore is made by the cutter.

In adjusting the cutter to its work, all that is necessary is to hold a vertically disposed straight edge on the portion 1^a of the guide cylinder in the path of the cutter, and then move the cutter out into engagement with the straight edge. Such a straight edge is indicated in dotted lines in Fig. 2 being designated by the numeral 10.

The ease with which this adjustment is made presents a tremendous advantage over those cutters which have to be adjusted in pairs on opposite sides of a guide cylinder, since it is very difficult to get any

two of them perfectly adjusted relatively to each other. My construction entirely dispenses with the necessity of any such delicate and tedious adjustments, and yet 5 gives a truer bore than is probably possible with a plurality of cutters simultaneously operating in the same hole.

In Fig. 2 of the drawings, I have shown 10 an arrangement for reborning by hand, in which I provide a threaded shank 11 having a handle 12 on its upper end, and a rigid block 13 on its lower end for engagement with the universal joint which is the same as that employed in the power driven tool 15 illustrated in Fig. 1. With this form of the device I may employ a fork 14 which can be entered in the valve seat in a Ford block when reborning a Ford cylinder by hand. Otherwise, the fork 14 may be omitted. 20

Whether I reborne by power or by hand, I prefer to employ the universal joint construction, as it causes the guide cylinder 1 to easily and accurately centre itself relatively to the hole that is being reborne, as well as adjusting it to the power bar 5, which with my construction does not have to be adjusted into perfect alinement with the longitudinal centre of the cylinder, but 30 will work all right whether it is perfectly adjusted or not.

My device will usually be operated on a power press in a vertical position, but it will also work well on a lathe in a horizontal position whenever it is found necessary or desirable to use it in that way. 35

Referring to the modification illustrated 40 in Fig. 3 of the drawings, the threaded shank 11^a passes through a cooperating threaded opening at 15 in the shank support 16. This support 16 has its two ends bent 45 downwardly forming the sections 17 and

18, the section 17 terminating in a single foot 19, and the section 18 terminating in a double foot 20. These feet are provided 45 with set screws 21, the single foot having one, and the double foot having two. By means of these screws the support 16 is rigidly secured to the top of the block, so that the tool will be held perfectly steady 50 and true.

I provide the threaded shank 11^a with very fine threads, to cause it to feed slowly to the work, and thereby give a very fine 55 bore.

Having thus described my invention, what I claim as new and desire to protect by Letters Patent is:—

A device of the character described, comprising an integral guide cylinder having 60 means therein for supporting a cutter; and means integral with the cylinder for connection with a drive shaft, said cylinder having an ample opening in its side for the cutter to extend out through to the work, and for the easy escape of borings into the interior of the cylinder, the rear side of the cutter being arranged to rest in engagement with the rear wall of said opening to brace 65 the tool against springing, whereby to prevent chattering of the tool, and to bring the opening practically in front of the cutter, for the purpose above set forth relative to the easy escape of shavings; said integral means for connection with the 70 drive shaft being located in advance of the centre of the cylinder in the guide part of the cylinder, whereby the force which drives and guides the cylinder is applied at a point 75 materially in advance of the centre of the cylinder.

In testimony whereof I affix my signature.

LLOYD M. BOATMAN.
